HYDRAULIC BACK-PRESSURE VALVE.

1,108,863.

Specification of Letters Patent. Patented Aug. 25, 1914.

Application filed June 6, 1914. Serial No. 843,425.

To all whom it may concern:

Be it known that we, OTTO G. HAEDIKE and ROBERT D. BRADEN, citizens of the United States, and residents of Chicago, in the county of Cook and State of Illinois, have invented certain new and useful Improvements in Hydraulic Back-Pressure Valves, of which the following is a specification.

10 Our invention relates to a hydraulic back pressure valve used in connection with acetylene cutting and welding apparatus.

The cutting or welding tool comprises an instrument having a single outlet opening and with two service lines or tubes leading to the single outlet opening. Through one of the service lines acetylene gas passes from a low pressure generator or from a suitable tank in which acetylene gas is stored; and 20 oxygen, under comparatively high pressure, passes through the other service line, so that the acetylene gas and oxygen meet in the cutting or welding tool and pass out through the single opening therein. This mixture of 25 acetylene gas and oxygen forms a highly combustible gaseous combination which, when ignited, produces the necessary heat for cutting or welding. Since the pressure in the oxygen tank is much greater than the 30 pressure within the acetylene generator, it is obvious that under certain conditions the ignited gases at the tool end might be carried back through the acetylene supply line or pipe into the acetylene generator, resulting in an explosion. To avoid such an 35 occurrence, we have devised a back pressure valve which places an effective water seal in the acetylene gas line whereby ignited gases entering the acetylene line, due to back pressure, will be instantly extinguished and in the event that the flame at the end of the tool is extinguished and back pressure is created, such as by the end of the tool being obstructed, the gases will pass out 40 through the back pressure valve and into a suitable container or into the atmosphere, thereby avoiding a collection of gases within the generator, a room or building.

A further object of the invention is to

provide a valve of the character described 50 which will be automatic in its operation to the extent that when back pressure has been created and is relieved, the valve will immediately adjust itself to a condition for further operation. 55

There are a number of details in our improved construction essential to its successful operation which will be hereinafter more specifically referred to and our improved structure, in its entirety, is shown in the accompanying drawings in which— 60

Figure 1 is a vertical section of my improved structure; Fig. 2 is a top plan view of Fig. 1; Fig. 3 is the section on the line 3—3 in Fig. 1; Fig. 4 is a section on the line 65 4—4 of Fig. 1; Fig. 5 is a section on the line 5—5 in Fig. 1; Fig. 6 is a section of the line 6—6 in Fig. 1; Fig. 7 is a perspective view of a portion of the apparatus.

Referring now more particularly to the 70 drawing, our improved valve comprises the casing 10 within which a main vertical gas tube 11 is disposed, the lower end of which is provided with threads 12 for threaded engagement with the threads 13 formed on the 75 bottom wall 14 of the casing 10. Near the lower end of the tube 11 a series of outlet openings 15 are formed and surrounding these outlet openings is a shell 16, the outer edge of which is provided with a series of 80 perforations 17. The casing 10 is divided into two compartments by a partition 18. The space above the partitions 18 may be considered as one compartment and the space below as another compartment. The 85 return tube 20, secured at one end to partition 18 and at its other end to the casing or shell 16, has its upper end opening into the upper compartment and its lower end opening into the lower compartment. A vent 90 tube 21, with its lower end disposed adjacent the shell 16, extends upwardly through the partition 18 and terminates beneath the baffle plate 22 that is secured to the tube 11. The baffle plate is provided with suitable 95 openings 23 and is of less diameter than the interior diameter of the tube 10, thereby leaving a margin between its periphery and

the inner wall of the casing 10. Above the shell 16 and surrounding the tubes 11 and 21, a spacing plate 24 is interposed. A baffle plate 22^a is arranged beneath the lower end 5 of the tube 21. The top of the tube 10 is inclosed by a cap 25 which is provided with a threaded boss 23 with which the upper end of the tube 11 has a threaded connection. Two openings are formed in the cap 10 25, the intake opening 27 communicating with the upper end of the tube 11 and the vent opening 28 communicating with the upper compartment of the casing 10. Suitable pipes 29 and 30 lead to the intake and 15 vent openings 27 and 28 respectively. A valve or outlet opening 31 is secured to the casing 10 opening thereinto below the partition 18 and a plug 32 has a screw threaded connection with the casing 10 near its 20 lower end. A generator (not shown) supplies acetylene gas to the main service line 33 (Fig. 7) and the casing 10 is connected to the main service line 33 by the supply pipe 29. The exhaust pipe 30 may be led 25 to any suitable point desired.

Referring now to the welding or cutting tool (which constitutes no part of my invention but which we deem necessary to show in order that the operation of our device may be completely described) this tool 30 comprises a nozzle 34, into which oxygen and acetylene gas are simultaneously conveyed. The acetylene gas is conveyed through the flexible tube 35 connected at 35 one end to the valve 31 and at its other end to the handle 36 of the nozzle 34 which also serves as a mixing chamber. Oxygen is stored in the tank 37 and conveyed from said tank through the tube 38 into the handle 36 40 so that the acetylene gas and oxygen enter the handle at substantially the same point and pass therethrough into the nozzle 34 and through the outlet opening therein whereupon the combined substances are ignited. The pressure within the acetylene 45 generator is slightly above atmospheric pressure while the pressure within the oxygen tank greatly exceeds the pressure in the generator, so that it will readily be perceived 50 that if the outlet opening in the nozzle 34 became clogged, a back pressure would be created that would carry the very highly explosive mixture of acetylene gas and oxygen back through the acetylene gas line and into 55 the generator, thereby necessarily resulting in an explosion in the event that ignited gases are so carried back or the mixture is otherwise ignited. To accomplish the complete object of our invention it is therefore 60 necessary to place a liquid within the casing 10 which will extinguish any ignited gases that may be carried into the casing by reason of back pressure and for the purpose of illustration we have shown a liquid within

the casing. The liquid within the casing is 65 under slight pressure thereby causing the level of the liquid in the tubes 20 and 21 to be slightly higher than the level of the liquid within the casing, and the acetylene gas that passes through the pipe 11 leaves the pipe 70 through the openings 15 and passes out through the opening 17 in the shell 16. The primary purpose of the openings 16 and 17 is to break any gas bubbles that may be formed when the acetylene gas passes 75 through the water or other liquid in the tube 11 and a screen 24^a is arranged above the shell 16 for a similar purpose. The acetylene gas from the main service line 33 therefore passes into the tube 11 and thence 80 into the lower compartment of the casing 10 rising through the liquid therein and passing out of the casing through the valve 31 and into the pipe 35 and through the combined handle and mixing chamber 36 into 85 the tool 34. When the oxygen in the tank 37 is released and the gases flowing from the end of the tool 34 are ignited, the hydraulic valve of course performs no function during 90 the normal operation of the apparatus but in the event that the opening at the end of the tool should, for any reason, become obstructed, the high pressure of the oxygen in the tank 37 will cause a back pressure in the apparatus and the combined oxygen and acetylene gas will travel back through the hose 35 into the casing 10. The high pressure of the oxygen will therefore cause the liquid in the lower compartment of the casing to rise 95 in the tubes 11, 20 and 21. As the liquid rises the water seal at the lower end of the tube 21 will be first broken and since there is a liquid column in the tube 11 as well as pressure therein from the acetylene gas, the back pressure gases will take the line of least 100 resistance thereby flowing into the tube 21 and out through the pipe 30 which is open to the atmosphere. Whatever liquid is forced upwardly through the pipe 21 by the 105 back pressure strikes the baffle plate 22 and 110 is collected within the upper compartment. Thereupon the gases pass around the baffle plate 22 and out into the atmosphere. It will be readily seen that when the obstruction of the end of the tool 34 is removed, 115 the excessive back pressure upon the liquid within the casing is relieved and therefore the liquid which has collected in the upper compartment will flow through the return pipe 20 into the lower compartment of the 120 casing, since the upper compartment is open to the atmosphere through the medium of the pipe 30.

Our improved hydraulic valve therefore is 125 automatic in its operation to the extent that it assumes its normal working condition when the back pressure is relieved and will continue to allow the passage of the acety-

lene gas therethrough and to always maintain an effective water seal within the acetylene gas pipe 11.

Having now described our invention—we 5 claim:

1. A hydraulic back-pressure valve comprising two compartments, an acetylene gas tube extending into one compartment, a vent tube in communication with both compartments, a return tube in communication with both compartments, an outlet opening in one compartment and a vent opening in the other compartment.

2. A hydraulic back-pressure valve comprising two compartments arranged in different vertical planes, an acetylene gas tube extending into the lower compartment, a vent tube in communication with both compartments, a return tube in communication with both compartments, a vent opening in the upper compartment and an outlet opening in the lower compartment.

3. A hydraulic back-pressure valve comprising a casing divided into two compartments, an acetylene gas tube extending through one compartment into the other compartment and having an opening in the latter compartment, a vent tube in communication with both compartments, a return tube in communication with both compartments, a vent opening in one compartment and an outlet opening in the other compartment.

4. A hydraulic back-pressure valve divided into two compartments, an acetylene gas tube extending through one compartment into the other compartment and having an opening adjacent the end thereof in the latter compartment, a vent tube in communication with both compartments, a return tube in communication with both compartments, a vent opening in one compartment adjacent one end of said vent tube and an outlet opening in the other compartment disposed between the ends of the return tube.

5. A hydraulic back-pressure valve comprising a main casing divided into two compartments, a gas tube extending through one compartment into the other compartment and having an opening near its lower end, a casing surrounding said opening and also provided with an opening, a vent tube in communication with both compartments and having its lower end arranged above the opening in said casing, a return tube in communication with both compartments and having its upper end arranged below the upper end of said vent tube, a vent opening in one compartment and an outlet opening in said casing into the other compartment and intermediate the ends of said return tube.

6. A hydraulic back-pressure valve comprising a main casing divided into two com-

partments, a gas tube extending through one compartment into the other compartment and having an opening near its lower end, a casing surrounding said opening and also provided with an opening, a vent tube in communication with both compartments and having its lower end arranged above the opening in said casing, a baffle-plate disposed above the upper end of said vent tube, a return tube in communication with both compartments and having its upper end arranged below the upper end of said vent tube, a vent opening in one compartment and an outlet opening in said casing into the other compartment and intermediate the ends of said return tube.

7. A hydraulic back-pressure valve comprising a main casing divided into two compartments, a gas tube extending through one compartment into the other compartment and having an opening near its lower end, a casing surrounding said opening and also provided with an opening, a vent tube in communication with both compartments and having its lower end arranged above the opening in said casing, a return tube in communication with both compartments and having its upper end arranged below the upper end of said vent tube and its lower end arranged below the opening in said casing, a vent opening in one compartment and an outlet opening in said casing into the other compartment and intermediate the ends of said return tube.

8. A hydraulic back-pressure valve comprising a main casing divided into two compartments, a gas tube extending through one compartment into the other compartment and having an opening near its lower end, a casing surrounding said opening and also provided with an opening, a vent tube in communication with both compartments and having its lower end arranged above the opening in said casing, a baffle-plate disposed above the upper end of said vent tube, a return tube in communication with both compartments and having its upper end arranged below the upper end of said vent tube and its lower end arranged below the opening in said casing, a vent opening in one compartment and an outlet opening in said casing into the other compartment and intermediate the ends of said return tube.

9. A hydraulic back-pressure valve comprising a main casing divided into two compartments, a gas tube extending through one compartment into the other compartment and having an opening near its lower end, a casing surrounding said opening and also provided with an opening, a vent tube in communication with both compartments and having its lower end arranged above the opening in said casing, a baffle-plate disposed above the upper end of said vent tube,

a baffle-plate disposed below the lower end of the vent tube, a return tube in communication with both compartments and having its upper end arranged below the upper end 5 of said vent tube and its lower end arranged below the opening in said casing, a vent opening in one compartment and an outlet opening in said casing into the other com-

partment and intermediate the ends of said return tube and a screen in said main casing 10 below the outlet opening.
